CLAIM

The ornamental design for a anchor for rope or the like,
as shown.

DESCRIPTION

FIG. 1 is a perspective view of an anchor for rope or
the like showing my new design;

FIGS. 2 and 3 are respectively top and bottom plan
views thereof; and

FIG. 4 is a front elevational view thereof, the rear ele-
vational, and right and left side elevational views
thereof being identical.

FIG. 1

FIG. 2

FIG. 3

FIG. 4
